ROTARY VALVE FOR INTERNAL-COMBUSTION ENGINES.

1,168,572.

Specification of Letters Patent. Patented Jan. 18, 1916.

Application filed January 23, 1913. Serial No. 743,778.

To all whom it may concern:

Be it known that I, GLENN R. SMITH, a citizen of the United States, residing at Los Angeles, in the county of Los Angeles and State of California, have invented new and useful Improvements in Rotary Valves for Internal-Combustion Engines, of which the following is a specification.

This invention relates to rotary valves for internal combustion engines, and the invention has for its object to provide improvements in valves of the type or character stated which will be superior in point of simplicity and inexpensiveness of construction and organization, durability or length of life, capability of long service without attention or repair or regrinding; positiveness and accuracy in operation, and which will be generally superior in efficiency and serviceability.

The invention relates particularly to rotary valves having a plurality of valve members which are co-acting, or interacting, the members being provided each with an exhaust port and an inlet port, means being provided for operatively actuating the valve members to bring the exhaust ports and the inlet ports alternately into registration with a suitable exhaust for the cylinder and a suitable inlet for the cylinder. The valve members are preferably conical or of truncated conical formation and coaxially arranged and have their working axes preferably at one end of the cylinder and arranged at right angles to the longitudinal axis of the cylinder.

Further particular objects of the invention contemplate the provision of such double acting valves which will be quick opening and quick closing with respect to the exhaust and inlet ports and in which the exhaust will traverse the valve members, properly confined, to pre-heat the incoming charge of gaseous explosive mixture and the provision incident to the general construction which will serve to agitate and thoroughly mix such incoming charge prior to its introduction to the cylinder.

Other objects concern the provision of valve members which will be positively seated, or, in the coaxial arrangement, nested one within the other, and both or all within the valve chamber, an incidental result being the effective prevention of valve smut-

ting. I am also able to provide for large port area, the opposite rotation of the valve members contributing to such possibility, without enlarging the period of open condition of either the exhaust or inlet. In the use of my improved valve, the pressure medium is thoroughly distributed and is prevented from confinement to local streams, and the perfect balance obtained in the operative conditions insures noiselessness of operation. The prompt and complete accommodation of the exhaust gases eliminates the resistance or back pressure upon the piston during the exhaust stroke, high efficiency being thus obtained. The improved valve means may be readily taken apart for purposes of repair, and access may be had to the working parts without the necessity of extensive taking down of the parts of the engine.

With the above and other objects in view, and the above substitute and equivalent means entering into the construction and organization of an embodiment of the same, the invention consists in the novel and useful formation, construction, relative arrangement and organization of parts, members and features, all as hereinafter described, shown in the drawings and finally pointed out in claims.

In the drawings: Figure 1 is a fragmentary longitudinal central sectional view of a portion of an internal combustion motor provided with valve means constructed and organized in accordance with the invention; Fig. 2 is a fragmentary view, partly in section, of members of the valve means in detached positions, and each partially separated from the other; Fig. 3 is a fragmentary elevation of drive means for the valve means looking in the direction of the arrow at the right hand side of Fig. 1; Fig. 4 is a fragmentary sectional view of the valve members taken upon the line x^4-x^4 , Fig. 1, and looking in the direction of the appended arrows; and Fig. 5 is a view similar to Fig. 4, taken upon the line x^5-x^5 , Fig. 1, and looking in the direction of the appended arrows.

Corresponding parts in all the figures are designated by the same reference characters.

Referring with particularity to the drawing, A designates the cylinder of an internal combustion motor of which B designates

the piston, the piston being shown at the charge-receiving and charge-compressing end of the cylinder, at which end likewise is installed the improved valve means C, 5 organized to embody the invention; D designating drive means or actuating means for the valve means C. Such valve means comprise a plurality of members, of which two, c and d, are shown in the drawing, 10 such valve members being preferably hollow and of truncated conical formation, and installed coaxially with the smaller member d, housed within the larger member c. The member d, provided with a rotatable 15 exhaust port 4 and a rotatable inlet port 5, respectively formed adjacent to the larger and smaller ends of the member; and the member c is provided with a rotatable 20 exhaust port 6 and a rotatable inlet port 7, respectively formed adjacent to the larger and smaller ends of the member. The ports are so formed and inter-related or relatively 25 spaced, in the two valve members, that when the ports 4 and 6 are in registration they both register with an exhaust passage 8 at 30 the end of the cylinder A, exhaust being through an exhaust duct 9 which ranges through the valve member d concentrically therewith and is curved downwardly at one 35 terminus to communicate with the exhaust port 4, the other terminus communicating with the normal atmosphere either directly or through any preferred form of exhaust pipe, not shown, which may readily be attached to register with the duct 9 at 10. Furthermore, likewise, the inlet ports 5 and 7 are out of registration when the exhaust ports 4 and 6 are in the positions last 40 stated; and when the inlet ports 5 and 7 are in registration with an inlet passage 11 at the end of the cylinder, the exhaust ports 4 and 6 have passed out of the registering positions, by rotation, such exhaust port registration being timed to transpire just 45 prior to the registering of the inlet ports with the inlet passage. The valves are adapted to be used with motors of the four-stroke-cycle type, calling for two complete excursions of the piston for one intake, compression, firing and scavenging; the inner 50 end of the member d, otherwise closed, is preferably perforated, slotted or otherwise open in part, as at 12, communicating with the chamber within a bell-shaped spider 13 carrying the member c, through which in 55 turn passes a coaxial shaft 14 included with in the drive means D; an inlet chamber 15 being provided around the spider 13 through which spider the charge passes to 60 the interior of the member d, a passage or duct 5^a being provided therein exteriorly of the exhaust duct 9, whence the charge passes to the inlet port 5 and through the inlet port 7 to the inlet passage 11. The 65 spider 13 is journaled in the wall of the

chamber 15, as at 16, and the shaft 14, journaled in the spider 13, as at 17. The outer valve member C, within which the smaller valve member d is rotatably mounted, is housed within a valve casing 18, which may be water jacketed, and is mounted upon the end of the cylinder. The drive means D, in addition to the shaft 14, comprises spiral gears 19 and 20 respectively keyed upon the spider 13 and the shaft 14, and other 70 spiral gears 21 and 22 respectively mesh with the first named spiral gears, and keyed upon the shafts 23 and 24 respectively, which are operated in step by spur gears 25 and 26 respectively upon the shafts 23 and 24, one of said shafts 23 being directly driven by a chain drive 27 operated by the engine.

It will be understood that the gears 19 and 20 serve to continuously rotate the spider 13 and the valve member c, and the shaft 14 and the valve member d, respectively, in opposite directions, so that the inlet ports 5 and 7 and the outlet ports 4 and 6 are properly timed to produce the proper sequences of admission and exhaust, as above stated. The charge or pressure medium taken in through the inlet chamber 15 is whirled and agitated and thoroughly mixed by the rotating arms of the spider 13, and the opposite rotating perforated end of the valve member d. The particular formation of this spider and of the perforated or partly open end of the member d may be varied in accordance with preference. The charge or pressure medium then enters the member d, where it is pre-heated or re-heated, and in this condition fed to the cylinder to and through the inlet passage 11. The exhaust traversing the exhaust pipe 9 produces this re-heating effect upon the charge or medium as it traverses the inner valve member d. It will be noted that the timing of the valve members may be accurately predetermined and maintained, and the other objects of the invention initially pointed out, will be found to flow from practice of the invention and utilization of the features specified in designing the embodiment shown in the drawing.

It is manifest that many variations and departures may be made with respect to the specific disclosure shown in the drawing and set out in the description, all within the spirit of the invention in adapting the invention to the varying conditions of use and service.

Having thus described my invention, I claim and desire to secure by Letters Patent:

1. An engine provided with valve means comprising two truncated conical coaxially arranged valve members, each of which is provided with an inlet port and an exhaust

port, the inlet ports being adapted to jointly register with an inlet passage to the cylinder, and the exhaust ports to jointly register with an exhaust passage from the cylinder; means for admitting pressure medium to one end of the inner member, and means for oppositely rotating both said members; said outer member being provided with a rotating spider upon which such member is mounted, and said inner member being provided with a shaft journaled in said spider and upon which such inner member is mounted.

2. An engine provided with valve means comprising two truncated conical coaxially arranged valve members, each of which is provided with an inlet port and an exhaust port, the inlet ports being adapted to jointly register with an inlet passage to the cylinder, and the exhaust ports to jointly register with an exhaust passage from the cylinder; means for admitting pressure medium to one end of the inner member, and means for oppositely rotating both said members; said outer member being provided with a rotating spider upon which such member is mounted, and said inner member being provided with a shaft journaled in said spider and upon which such inner member is mounted; and an inlet chamber within which said spider is journaled and through which the pressure medium is fed through said spider and to said inner valve member through said end thereof.

3. An engine provided at one end with a valve casing, coaxial valve members rotatably mounted in the casing and provided each with an exhaust port and an inlet port, the

exhaust ports being adapted to register with each other and the inlet ports being adapted to register with each other in proper sequence and to respectively register with exhaust and inlet passages from and to the cylinder, a pressure medium inlet chamber, a spider journaled in the same and carrying one valve member, a shaft journaled in the spider and carrying another valve member, said last named valve member being perforated at one end, and means for oppositely rotating the spider and the shaft.

4. An engine provided at one end with a valve casing, coaxial valve members rotatably mounted in the casing and provided each with an exhaust port and an inlet port, the exhaust ports being adapted to register with each other and the inlet ports being adapted to register with each other in proper sequence and to respectively register with exhaust and inlet passages from and to the cylinder, a pressure medium inlet chamber, a spider journaled in the same and carrying one valve member, a shaft journaled in the spider and carrying another valve member, said last named valve member being perforated at one end, and means for oppositely rotating the spider and the shaft; there being an exhaust pipe within the latter valve member and adapted to register with said exhaust ports.

In testimony whereof, I have signed my name to this specification in the presence of two subscribing witnesses.

GLENN R. SMITH.
